DRIVING MECHANISM.

1,235,538.

Specification of Letters Patent.

Patented July 31, 1917.

Application filed October 19, 1916. Serial No. 126,481

To all whom it may concern:

Be it known that I, ISAAC S. DEMENT, a citizen of the United States, residing at Dayton, in the county of Montgomery and State of Ohio, have invented certain new and useful Improvements in Driving Mechanism, of which the following is a specification, reference being had therein to the accompanying drawing.

10 This invention relates to driving mechanism and is designed more particularly to take the place of the compensating gearing ordinarily employed in motor driven vehicles, to permit of the relative movement of the two driving wheels.

As is well known, the ordinary compensating gearing is open to at least one serious objection. It causes the larger part of the power to be applied to that wheel to the movement of which the less resistance is offered, thus frequently preventing the movement of such a vehicle under its own power, where such movement would be easily accomplished if the power were applied equally to 25 both wheels, or to the wheel to which the greater resistance was offered.

The object of the present invention is to provide a compensating mechanism which will apply the power to that wheel having 30 the slowest movement; and to provide such a mechanism which will be of a simple, durable character, and which will be positive in its operation.

To this end a further object of the invention is to provide such a mechanism having 35 driving pawls which will be positively shifted from one position to the other when the direction of the movement of the driving member is reversed.

40 The other objects of the invention will appear as the mechanism is described in detail.

In the accompanying drawings Figure 1 is a side elevation of a mechanism embodying 45 my invention, with the driving gear partly broken away; Fig. 2 is a sectional view taken centrally through the same; Fig. 3 is a side elevation of the actuating device and its pawls; Fig. 4 is a side elevation, partly 50 broken away, of a different embodiment of the invention; Fig. 5 is a vertical sectional view taken centrally of Fig. 4; Fig. 6 is an elevation partly in section showing the invention applied directly to the driving 55 wheels of an automobile; Fig. 7 is a sectional view taken on the line α — α on Fig. 6 look-

ing in the direction of the arrows; and Fig. 8 is a detail view of a modified form of the invention.

In these drawings I have illustrated one 60 embodiment of my invention and have shown three different applications of the same to the rear axle of an automobile, but it will be understood that the invention is not limited to motor driven vehicles but may be 65 useful in any position in which a compensating drive is desired. In each of the three forms of the mechanism herein illustrated I have shown the same as comprising a driving member consisting of at least two parts 70 which are connected together, and one of which is capable of a limited movement relatively to the other. The power is applied directly to that part of the driving member which is movable relatively to the other part 75 and is transmitted to said other part thereof by means of a connection between the two parts. The second part is provided with means for connecting the same with one or more driven members, such as pinions, or 80 toothed wheels, on the adjacent ends of the two parts of the axle. The devices for connecting the last mentioned part of the driving member with the driven members are controlled by the movement of the first part 85 relatively to the last mentioned part of said driving member and, in the present instance, I have utilized an actuating device which is shifted by this relative movement to actuate the connecting devices. 90

As shown in Figs. 1 and 2 the rear axle is divided into two parts, 1 and 2, which are arranged in alinement and which have rigidly secured thereto toothed members, or ratchet wheels, 3 and 4, which are here 95 shown as ordinary spur gears, and which constitute the driven members of the mechanism. The driven members are spaced apart a distance sufficient to receive between them a driving member, and one part of the 100 axle, in the present instance part 1, projects beyond the inner face of its driven member and affords a bearing for said driving member. The driving member may take various forms but preferably it consists of two main 105 parts, one of which is capable of a limited rotatory movement relatively to the other, and it is shown in Figs. 1 and 2 as comprising an inner part 5 which is circular in form and is rotatably mounted on the inner 110 end of the part 1 of the axle. Mounted upon the inner part 5 of the driving member is an 115 off-set pawl or pawl toothed member 20

2

outer part 6 which is annular in shape and is capable of a limited circumferential movement relatively to the inner part of the driving member. This outer part of the driving member is provided with means whereby power may be applied thereto, and, in the present instance, has a series of beveled gear teeth 7 adapted to mesh with the beveled pinion 8 on a driving shaft 9. Suitable means are provided for connecting together the two parts of the driving member and causing them to act as a unit, except when there is a limited relative movement as above mentioned. In the present construction the inner part 5 has rigidly secured to the opposite sides thereof guide members 10, which are here shown as annular plates rigidly secured to the inner part by means of rivets 11, projecting beyond the periphery of said inner part and embracing the inner portion of the outer part of the driving member so as to retain the two parts in radial alinement but to permit the outer part to have circumferential movement on the inner part. The movement of the outer part of the driving member relatively to the inner part thereof is limited by means of laterally extending projections carried by said outer part, and consisting in the present device of a pin 12 extending through the same, and through slots 13 in the connecting plates 10. Mounted on each side of the driving member and connected with the inner part thereof is a pair of connecting devices, or pawls 14 and 15, which are adapted to be alternately moved into engagement with the coöperating toothed member and to rotate the same in one direction or the other, and which are yieldably mounted to permit the toothed member to run ahead of the pawl which is in operative engagement therewith. Thus when the resistance offered to both wheels is substantially the same the power will be applied equally thereto, but should one wheel meet with a resistance greater than that offered to the other wheel, which resistance would have a tendency to slow down the movement of the wheel, and consequently its toothed member which is carried by the axle, the pawl will remain in engagement therewith and provide a direct connection between the same and the source of power, so that the power is applied always to that wheel having the slowest movement, regardless of whether or not the other wheel is running free. Suitable connections are established between the pawls on each side of the driving member and the outer part of the driving member to cause the positions of the pawls in relation to their coöperating toothed members to be reversed by the movement of the outer part of the driving member relatively to the inner part thereof. The inner and outer parts of the driving member may be so mounted that the frictional resistance offered to the movement of the outer part will always be less than that offered to the movement of the inner part thereof, thereby causing the outer portion of the driving member to always move relatively to the inner part thereof, when its direction of movement is reversed, before movement is imparted to the inner part of the driving member, thus causing the pawls to be reversed. However, to avoid any possibility of rotation being imparted to the inner part of the driving member before the outer part thereof is moved about the circumference thereof to shift the pawls, which might be due to any one of several conditions, such as the entrance of foreign matter into the mechanism, I have provided means for retarding the movement of the inner part of the driving member until the relative circumferential movement of the outer part thereof has been accomplished, when the retardation will cease. These results may be secured in various ways, but I prefer that shown in Figs. 1 and 2 of the drawings, in which each pair of pawls 14 and 15 is shown as pivotally mounted on an actuating device 16, which, in turn, is pivotally mounted on the inner part of the driving member, the axis of the actuating member being preferably arranged adjacent to the axes of the two pawls. The actuating device, or plate 16 is connected with the outer part of the driving member so as to be rocked about its pivotal center by the movement of the outer part of the driving member relatively to the inner part thereof, and thereby moving one pawl away from its coöperating toothed member, and moving the other pawl toward said toothed member. In the present instance this connection is provided by extending the pin 12 beyond the guide plates 10 and into the two actuating devices 16. The pawls 14 and 15 are shown as provided with outwardly extending arms 17 and 18 between which is confined a stiff spring 19 which serves to hold the pawls in engagement with stops 20, when in idle position or being moved to idle position. The stops 20 are carried by the actuating device and are arranged to the rear of the respective arms 17 and 18. The movement imparted to the actuating device 16 by the outer part of the driving member is greater than is necessary to move the idle pawl into operative relation to the coöperating toothed member, and hence after the pawl is in engagement with the toothed member the actuating device will continue its movement and carry the stop 20 away from the arm of the pawl thus enabling the full strength of the spring 19 to be utilized in holding the pawl in engagement with the toothed member. The pressure of the pawl against the toothed member offers a frictional resistance to the relative movement of these parts and when

the driving member is moved in a reverse direction the resistance offered to the movement of the pawl over the toothed member will retard the movement of the inner part 5 of the driving member and cause the outer part thereof to be moved relatively thereto. The stop 20 having been carried beyond the arm of the pawl which is in engagement with the toothed member it will be apparent 10 that when the direction of movement of the driving member is reversed a certain amount of initial movement will be imparted to the actuating device before the stop engages the arm of the pawl. This initial movement is 15 sufficient to move the idle pawl into operative relation to the toothed member and the spring 19 will hold the first, or operative, pawl in engagement with the toothed member until the stop 20 has engaged its arm, 20 when the further movement of the actuating device will lift the pawl out of engagement with the toothed member. Thus practically the full force of the spring is utilized to hold the first pawl in frictional engagement with 25 the toothed member until the second, or idle pawl, has been moved into operative relation to the toothed member. In this manner I insure the movement of the idle pawl into its operative position upon each reversal of 30 the directional movement of the driving member and cause the retardation of the movement of the inner part to cease as soon as the movement of the outer part of the driving member relatively to the inner part 35 thereof has been completed. It will be understood, of course, that the tension of the spring 19 is not so great as to interfere with the yielding movement of the pawl when the toothed member runs ahead of the driving 40 member.

In Figs. 4 and 5 I have shown another form in which the invention may be applied. As here shown the two parts of the axle are provided with toothed members 3 and 4, as 45 hereinbefore described, but instead of arranging the driving member between the toothed members it is mounted on the axle at the side thereof. As shown in these figures that part of the driving member to 50 which the power is directly applied, which has been designated as the outer member, comprises a beveled gear 21 which is mounted directly upon one part of the axle, adjacent to the corresponding toothed driven 55 member 4. Secured to the gear 21 is a frame, here shown as a housing 22, mounted on the other part of the axle and having at its outer edge a flange 23, which is connected with the gear 21 by means of screws 24. 60 Mounted about the respective parts of the axle are two plates 25 constituting the other, or inner part, of the driving member. These plates are arranged close to the body of the gear 21 and to the wall of the housing 22, 65 respectively, and, in the present instance, are rotatably mounted on shoulders, or hubs, formed on the respective driven members, although it will be obvious that it may be mounted in any suitable manner. Each plate 25 has pivotally mounted thereon a 70 pawl actuating device 26, which is connected with the outer part of the driving member by pins 27 which extend through slots 28 in the respective plates 25, and are mounted respectively in the body of the gear 21 and 75 in the housing 22. Mounted on these actuating devices are pawls 29 similar in construction and operation to those above described. It will be noted that this form of the device differs but little from that shown 80 in Figs. 1 and 2, except in the relative positions of the parts and the difference in the construction of the outer part of the driving member to permit it to be mounted directly upon the axle. This construction follows more closely the present arrangement 85 of compensating gearings and, under certain conditions, would be preferable.

In Figs. 6 and 7 I have shown a further rearrangement of the mechanism to enable 90 a one piece axle to be employed. To this end I have secured the driven members, or toothed wheels, 30, directly to the ground wheels 31, and have mounted the same loosely on the respective ends of the axle. 95 Power is applied to the axle through the medium of the outer part of the driving member, which as here shown comprises not only the beveled gear 32, which meshes with a beveled pinion 33 on a driving shaft 34, 100 but also includes plates 35, which are here shown as disk-like in form, and which are rigidly secured to the axle near the respective toothed members 30. Mounted on the axle between the members 35 of the outer 105 part of the driving member and the corresponding driven members are rotatable plates 36, constituting the inner part of the driving member and carrying pawl actuating devices 37 and pawls 38, which act 110 upon the driven members, and which are substantially the same in construction and operation as those heretofore described. The mechanism is inclosed within a suitable housing, which preferably constitutes a 115 brake drum for the wheel, as shown at 39. This form of the device is very compact and simple in its construction, and overcomes the necessity of forming the axle in two parts and at the same time provides for 120 the relative movement of the two ground wheels. The power from the driving member will be applied always to that wheel which is moving at the slowest speed and the other wheel will be free to rotate at a speed 125 which will accommodate it to any condition without regard to the speed of rotation of the wheel to which the power is applied.

In Fig. 8 of the drawings I have illustrated a modified form of the device in 130

which the pawls, 41 and 42, of each part, are formed in a single piece and are pivotally mounted on the axis of the actuating member 43. The outer part of the pawl structure is flat and is engaged by a spring 44 mounted at its ends in pins 45, carried by the actuating plate. This spring causes the pawls to move normally with the actuating plate but permits of their movement independently thereof to enable the toothed member to move relatively thereto.

In the ordinary operation of the mechanism there is no liability of rearward movement being imparted to the actuating device, to release the operative pawl, except when positive rearward movement is imparted to the outer part of the driving member. The spring 19 would not have sufficient strength to shift those parts of the mechanism which would have to move in order to permit the movement of the actuating device. However, under certain circumstances it might be desirable to provide means for positively preventing this movement of the actuating device until rearward movement had been imparted to the driving wheel, and I have shown in Figs. 1 and 2 a device which will positively lock the actuating device against movement and which will be released only by the movement of the outer part of the driving member. This device, in the form here illustrated, comprises a latch 46 pivotally mounted on one of the plates 10 of the inner part of the driving member and having near its free end a notch or recess, 47 to receive a pin 48 which is carried by the actuating device 16. This latch is in the form of a curved arm and has on its inner side a double shoulder, or cam surface, 49, which bears against the pin 12, by means of which the actuating device is connected with the outer part of the driving member, this pin being extended beyond the face of the actuating device to permit of its engagement. The opening in the actuating device through which the pin 12 extends is elongated in the direction of movement of the pin, as shown at 50. The cam surface 49 of the latch is so arranged with relation to the opening 50 that when the actuating device is at the extreme limit of its movement in either direction, and the pin is at the end of the opening the cam surface will be out of alinement with the pin, thus permitting the latch to move inward about its axis until the notched end thereof has embraced the pin 48 thereby locking the actuating device against movement. Upon the first movement of the outer part of the driving member in a reverse direction the pin 12 will move in the opening 50 relatively to the actuating device and will rock the latch about its axis, away from the pin 48, freeing the actuating device and permitting the latter to move along with the outer part of

the driving member when the pin 12 has engaged the end of the elongated opening 50. When the actuating device has reached the limit of its movement the pin will have passed the cam surface of the latch, thus permitting the latter to again move to its locking position. Any suitable means can be provided for imparting inward movement to the latch, but I have, in the present instance, shown a spring 51 for imparting this movement to the latch.

The operation of the device will be clearly understood from the foregoing description and it will be apparent that I have provided a compensating driving mechanism which is very simple in its construction, and is of such a character that it will be very strong and durable as is highly essential in mechanisms of this kind; that the construction is such that the larger amount of power will always be applied to that wheel of a motor driven vehicle which meets with the greater resistance to its movement, and therefore power will be applied where it is most needed; that either wheel can run ahead of the other without regard for the speed at which said other wheel is moving, thus absolutely eliminating the slipping of either wheel when the vehicle is traveling on a curved line; and that the construction is such that there is no liability of the pawls failing to shift when the direction of the movement of the driving mechanism is reversed, but that the shifting movement will always take place and the connection between the driving member and the driven member will be direct and positive.

While I have shown and described one embodiment of my invention, together with several arrangements of the mechanism, I wish it to be understood that I do not desire to be limited to the details thereof as various modifications will occur to a person skilled in the art. Further I wish it to be understood that the terms "outer part" and "inner part" as employed in the specification and claims are used as a convenient method to identify the two parts of the driving member and are not intended to limit the mechanism to any particular arrangement. Although in each of the three applications of the invention here illustrated, that part of the driving member to which the power is first applied is, strictly speaking, an outer part, and the other part is an inner part, it is nevertheless quite possible to otherwise arrange the mechanism without materially modifying the functions of the parts thereof, and such rearranged mechanisms would be the full equivalent of those called for by the claims.

Having now fully described my invention, what I claim as new and desire to secure by Letters Patent is:

1. The combination with a driven mem-

- ber, of a driving member comprising two parts operatively connected to cause power to be transmitted from one to the other, one of said parts being capable of a limited movement relatively to the other part, means to apply power to the first-mentioned part, an actuating device carried by the last-mentioned part, and connected with the first-mentioned part, and means actuated by said device to cause power to be transmitted from said driving member through said actuating device to said driven member.
2. The combination with a rotatable driven member, of a driving member rotatable about an axis coincident with the axis of said driven member, and comprising two parts operatively connected to cause power to be transmitted from one to the other, and one of which is mounted for a limited 5 rotatory movement relatively to the other, means to apply power to that part which is capable of said relative movement, an actuating device movably mounted on said other part and connected with the first-mentioned part, and a connecting device controlled by the movement of said actuating device to establish a driving connection between said driving member, said actuating device and said driven member.
3. The combination with driven members rotatable about a common axis, of a driving member comprising a part to which power is applied, said part having connected therewith, to receive power therefrom, other 10 parts mounted for rotation about said common axis, said first-mentioned part being capable of a limited movement relatively to the last-mentioned parts, actuating devices mounted on said last-mentioned parts and connected with the first-mentioned part, whereby the relative movement of the first-mentioned part will shift the positions of said actuating devices, and connecting devices controlled by the movement of the respective actuating devices to establish driving 15 connections between said driving member and said driven members, through the respective actuating devices.
4. The combination with toothed driven members rotatable about a common axis, of a driving member comprising a gear rotatable about said axis, plates rotatable about said common axis, arranged adjacent to the respective driven members and connected 20 with said gear, said gear being capable of a limited rotatory movement relatively to said plates, pawls carried by the respective plates, and connections between said pawls and said gear to cause said pawls to be moved into driving engagement with the respective driven members by the movement of said gear relatively to said plates.
5. The combination with driven members of a driving member comprising a part rotatable about a common axis, a driving member comprising a gear rotatable about 25 said axis, plates rotatable about said common axis, arranged adjacent to the respective driven members and connected with said gear, said gear being capable of a limited rotatory movement relatively to said plates, actuating devices pivotally mounted on the respective plates and connected with said gear, whereby the movement of said gear relatively to said plates will impart movement to said actuating devices, and connecting devices controlled by the movement of said actuating devices to establish a driving connection between said actuating devices and the respective driven members.
6. The combination with a rotatable toothed member, of a driving member mounted for rotation about the axis of said toothed member and comprising a part mounted adjacent to said toothed member, and a second part operatively connected with the first-mentioned part and capable of a limited rotatory movement relatively thereto, means to apply power to the second part of said driving member, a pair of pawls supported by the first part of said driving member and adapted to transmit power to said toothed member, and means actuated by the relative movement of the second part of said driving member to simultaneously impart bodily movement to said pawls to move one of the same into and the other out of driving engagement with said toothed member, said pawls being capable of yielding movement relatively to said toothed member, whereby power may be transmitted from said second part of said driving member through said pawls to said toothed member, and said toothed member may run ahead of said driving member.
7. The combination with a rotatable toothed member, of a driving member comprising a part mounted adjacent to said toothed member for rotation about the axis thereof, a second part capable of limited rotatory movement relatively to the first part, means to apply power to the second part of said driving member, a pawl supported by the first part of said driving member adjacent to said toothed member, an actuating device mounted on said first part of said driving member and connected with said pawl to move the same into and out of driving engagement with said toothed member, and connections between said actuating device and the second part of said driving member to cause movement of the latter relatively to said first part to shift said actuating device and reverse the positions of its pawls relatively to said toothed member.
8. The combination with toothed members mounted for rotation about a common axis, of a driving member comprising a part rotatable about 100 the common axis thereof, 105
9. The combination with driven members of a driving member comprising a part rotatable about a common axis, a driving member comprising a gear rotatable about 110 said axis, plates rotatable about said common axis, arranged adjacent to the respective driven members and connected with said gear, said gear being capable of a limited rotatory movement relatively to said plates, actuating devices pivotally mounted on the respective plates and connected with said gear, whereby the movement of said gear relatively to said plates will impart movement to said actuating devices, and connecting devices controlled by the movement of said actuating devices to establish a driving connection between said actuating devices and the respective driven members.
10. The combination with a rotatable toothed member, of a driving member comprising a part mounted adjacent to said toothed member for rotation about the axis thereof, a second part capable of limited rotatory movement relatively to the first part, means to apply power to the second part of said driving member, a pawl supported by the first part of said driving member adjacent to said toothed member, an actuating device mounted on said first part of said driving member and connected with said pawl to move the same into and out of driving engagement with said toothed member, and connections between said actuating device and the second part of said driving member to cause movement of the latter relatively to said first part to shift said actuating device and reverse the positions of its pawls relatively to said toothed member.
11. The combination with driven members of a driving member comprising a part rotatable about a common axis, a driving member comprising a gear rotatable about 120 said axis, plates rotatable about said common axis, arranged adjacent to the respective driven members and connected with said gear, said gear being capable of a limited rotatory movement relatively to said plates, actuating devices pivotally mounted on the respective plates and connected with said gear, whereby the movement of said gear relatively to said plates will impart movement to said actuating devices, and connecting devices controlled by the movement of said actuating devices to establish a driving connection between said actuating devices and the respective driven members.
12. The combination with toothed members mounted for rotation about a common axis, of a driving member comprising a part rotatable about 125 the common axis thereof, 130

- 6 a second part capable of a limited rotatory movement relatively to the first part, means to apply power to the second part of said driving member, a pair of pawls supported by the first part of said driving member adjacent to each of said toothed members, actuating devices mounted on said first part and connected with said pawls to move the same into and out of driving engagement with the respective toothed members, and connections between said actuating devices and the second part of said driving member, whereby the relative movement of the latter will cause the positions of the pawls of each pair to be reversed. 70
- 10 9. The combination with toothed members mounted for rotation about a common axis, of a driving member comprising a part mounted for rotation about the common axis of said toothed members, a second part capable of a limited rotatory movement relatively to the first mentioned part, means to apply power to said second part of said driving member, actuating devices mounted 75 on said first-mentioned part of said driving member, pawls connected with the respective actuating devices, arranged to be moved into driving engagement with the respective toothed members and capable of yielding movement relatively thereto, and connections between said actuating devices and said second part of said driving member to cause said pawls to engage the respective toothed members and thus cause power to be transmitted through said actuating devices and said pawls to said toothed members. 80
- 15 10. The combination with a driven member, of a driving member comprising two parts connected one to the other, one of said parts being capable of a limited movement relatively to the other part, means to apply power to the first mentioned part of said driving member, an actuating device carried by the last mentioned part of said driving member and connected with said first mentioned part thereof, means actuated by said device to connect said driving member with said driven member, and means to retard the movement of said last mentioned part until the first mentioned part has moved relatively thereto. 85
- 20 11. The combination with a rotatable toothed member, of a driving member comprising a part mounted adjacent to said toothed member for rotation about the axis thereof, and a second part capable of a limited rotatory movement relatively to the first part, means to apply power to said second part of said driving member, pawls connected with said first part of said driving member, means controlled by the movement of the second part of said driving member relatively to the first part thereof 90 to move said pawls alternately into and out of operative relation to said toothed member, and means for retarding the movement of said first part of said driving member until the second part has moved relatively thereto. 95
- 25 12. The combination with toothed members mounted for rotation about a common axis, of a driving member comprising a part mounted adjacent to said toothed members for rotation about the common axis thereof, and a second part capable of a limited rotatory movement relative to the first part, means to apply power to said second part of said driving member, a pair of pawls carried by said first part of said driving member adjacent to each of said toothed members, means controlled by the movement of the second part of said driving member relatively to the first part thereof to move the pawls of each pair alternately into and out of operative relation to the corresponding toothed member, and means for retarding the movement of said first part of said driving member until the second part has moved relatively thereto. 100
- 30 13. The combination with a rotatable toothed member, of a driving member comprising a part mounted adjacent to said toothed member for rotation about said axis thereof, and a second part capable of a rotatory movement relatively to said first part, means to apply power to said second part of said driving member, an actuating device movably mounted on said first part of said driving member and connected with the second part thereof, a pair of pawls connected with each of said actuating devices and arranged to be moved alternately into and out of operative relation to said toothed member, and means for retarding the movement of said first part of said driving member until the second part thereof has moved relatively thereto. 105
- 35 14. The combination with toothed members mounted for rotation about a common axis, of a driving member comprising a part mounted adjacent to said toothed members for rotation about said common axis thereof, and a second part capable of a limited rotatory movement relatively to the first part, means to apply power to the outer part of said driving member, actuating devices pivotally mounted on said inner part of said driving member and connected with the outer part thereof, a pair of pawls connected with each of said actuating devices and arranged to coöperate with the respective toothed members, and means to retard the movement of said first part of said driving member until the second part thereof has moved relatively thereto. 110
- 40 15. The combination with toothed members mounted for rotation about a common axis, of a driving member comprising a part mounted adjacent to said toothed members for rotation about said common axis thereof, and a second part capable of a limited rotatory movement relatively to the first part, means to apply power to the outer part of said driving member, actuating devices pivotally mounted on said inner part of said driving member and connected with the outer part thereof, a pair of pawls connected with each of said actuating devices and arranged to coöperate with the respective toothed members, and means to retard the movement of said first part of said driving member until the second part thereof has moved relatively thereto. 115
- 45 16. The combination with toothed members mounted for rotation about a common axis, of a driving member comprising a part mounted adjacent to said toothed members for rotation about said common axis thereof, and a second part capable of a limited rotatory movement relatively to the first part, means to apply power to the outer part of said driving member, actuating devices pivotally mounted on said inner part of said driving member and connected with the outer part thereof, a pair of pawls connected with each of said actuating devices and arranged to coöperate with the respective toothed members, and means to retard the movement of said first part of said driving member until the second part thereof has moved relatively thereto. 120
- 50 17. The combination with toothed members mounted for rotation about a common axis, of a driving member comprising a part mounted adjacent to said toothed members for rotation about said common axis thereof, and a second part capable of a limited rotatory movement relatively to the first part, means to apply power to the outer part of said driving member, actuating devices pivotally mounted on said inner part of said driving member and connected with the outer part thereof, a pair of pawls connected with each of said actuating devices and arranged to coöperate with the respective toothed members, and means to retard the movement of said first part of said driving member until the second part thereof has moved relatively thereto. 125
- 55 18. The combination with toothed members mounted for rotation about a common axis, of a driving member comprising a part mounted adjacent to said toothed members for rotation about said common axis thereof, and a second part capable of a limited rotatory movement relatively to the first part, means to apply power to the outer part of said driving member, actuating devices pivotally mounted on said inner part of said driving member and connected with the outer part thereof, a pair of pawls connected with each of said actuating devices and arranged to coöperate with the respective toothed members, and means to retard the movement of said first part of said driving member until the second part thereof has moved relatively thereto. 130

bers for rotation about the common axis thereof, and a second part capable of a limited rotatory movement relatively to the first part thereof, means to apply power to said second part of said driving member, pairs of oppositely extending pawls pivotally mounted on said first part of said driving member, means actuated by the movement of said second part of said driving member relatively to said first part thereof to move the pawls of each pair alternately into and out of operative relation to the respective toothed members, and means to retard the movement of said first part until said second part has completed its movement relatively thereto.

16. The combination with toothed members mounted for rotation about a common axis, of a driving member comprising a part mounted adjacent to said toothed members for rotation about the common axis thereof, and a second part capable of a limited rotatory movement relatively to the first part thereof, means to apply power to said second part of said driving member, pairs of oppositely extending pawls pivotally mounted on said first part of said driving member, means actuated by the movement of said second part of said driving member relatively to said first part thereof to move the pawls of each pair alternately into and out of operative relation to the respective toothed members, and means to cause that pawl which is in engagement with said toothed member to frictionally engage the same until the other pawl has been moved into operative relation thereto.

17. The combination with a rotatable toothed member, of a driving member comprising a part mounted for rotation about the axis of said toothed member, and a second part capable of a limited rotatory movement relatively to the said first part thereof, means to apply power to said second part of said driving member, a pair of pawls mounted on said driving member, means actuated by the movement of said second part of said driving member relatively to the first part thereof, to move one pawl into and the other out of operative relation to said toothed member, and means to cause that pawl which is in engagement with said toothed member to frictionally engage the same until the other pawl has been moved into operative relation thereto.

18. The combination with a rotatable toothed member, of a driving member comprising a part mounted for rotation about the axis of said toothed member, and a second part capable of a limited rotatory movement relatively to the said first part thereof, means to apply power to said second part of said driving member, a pair of oppositely extending pawls mounted on said driving member and having outwardly

extending arms, a spring confined between said arms, means to limit the movements of said arms under the influence of said spring, and means actuated by the movement of the second part of said driving member relatively to the first part thereof to move one of said pawls into and the other out of operative engagement with the co-operating toothed member.

19. The combination with toothed members mounted for rotation about a common axis, of a driving member comprising a part mounted adjacent to said toothed members for rotation about the common axis thereof, a second part capable of a limited rotatory movement relatively to the first part thereof, means to apply power to the second part of said driving member, a pair of oppositely extending pawls pivotally mounted on said driving member adjacent to each of said toothed members, the pawls of each pair having outwardly extending arms, springs confined between said arms, means to limit the movement of said arms under the influence of said springs, and means actuated by the movement of said second part of said driving member relatively to the first part thereof to move one of the pawls of each pair into and the other out of operative engagement with the co-operating toothed member.

20. The combination with toothed members mounted for rotation about a common axis, of a driving member comprising a part mounted adjacent to said toothed members for rotation about the common axis thereof, and a second part capable of a limited rotatory movement relatively to the first part thereof, means to apply power to the second part of said driving member, an actuating device movably mounted on said first part of said driving member adjacent to each toothed member, a connection between each of said actuating devices and said second part of said driving member to cause movement to be imparted to the former by the movement of the latter relatively to said first part of said driving member, a pair of pawls carried by each actuating device arranged to be moved alternately into and out of operative relation to said toothed member by the movement of said actuating device, and a spring tending to hold that pawl which is in operative relation to said toothed member in engagement therewith until the other pawl is moved into operative relation thereto.

21. The combination with a rotatable toothed member, of a driving member comprising a part mounted adjacent to said toothed member for rotation about the axis thereof, and a second part capable of a limited rotatory movement relatively to the first part thereof, means to apply power to said second part of said driving member, a device

- pivots mounted on said first part of said driving member and connected with said second part thereof, a pair of pawls pivotally mounted on said device and arranged to be moved alternately into engagement with the coöperating toothed member by the pivotal movement of said device, said pawls having outwardly extending arms, a spring confined between said arms and stops to limit the movement of said arms by said springs.
22. The combination with toothed members mounted for rotation about a common axis, of a driving member comprising a pair of plates rotatably mounted about the axis of said toothed members, and a second part connected with said plates and capable of a limited rotatory movement relatively thereto, actuating devices pivotally mounted on the respective plates and connected with the second part of said driving member, a pair of pawls carried by each of said actuating devices and adapted to be moved alternately into and out of operative relation with the coöperating toothed member by the pivotal movement of said actuating devices.
23. The combination with toothed members mounted for rotation about a common axis, of a driving member comprising a plurality of plates rotatable about the axis of said toothed members, and each having a slot, and a part mounted adjacent to said plates and having pins extending through the slots in the respective plates to connect said part therewith and to allow the same to have a limited movement relatively thereto, actuating devices pivotally mounted on said plates and connected with the respective pins, a pair of pawls carried by each of said actuating devices and arranged to be moved alternately into and out of engagement with the coöperating toothed members by the pivotal movement of the respective actuating devices.
24. The combination with a rotatable toothed member, of a driving member comprising a part mounted for rotation about the axis of said toothed member, and a second part connected with said first part and capable of a limited rotatory movement relatively thereto, means to apply power to said second part of said driving member, a pair of pawls connected with the first part of said driving member, means to impart bodily movement to said pawls to move one of them into and the other out of operative relation to said toothed member, said pawls being capable of independent yielding movement, and means to retain that pawl which is in operative relation to said toothed member in frictional engagement therewith during said bodily movement.
25. The combination with a rotatable toothed member, of a driving member comprising a part mounted for rotation about the axis of said toothed member, and a second part connected with said first part and capable of a limited rotatory movement relatively thereto, means to apply power to said second part of said driving member, a pair of pawls connected with the first part of said driving member, means to impart bodily movement to said pawls to move one of them into and the other out of operative relation to said toothed member, said pawls being capable of independent yielding movement, and means to retain that pawl which is in operative relation to said toothed member in frictional engagement therewith during said bodily movement.
26. The combination with a rotatable driven member, of a driving member rotatable about an axis coincident with the axis of said driven member and comprising two parts, one of which is mounted for a limited rotatory movement relatively to the other, means to apply power to that part which is capable of relative movement, connecting devices controlled by the relative movement of said part to connect said driving member with said driven member, and means controlled by the movement of said part to hold said connecting device against movement.
27. The combination with a rotatable driven member, of a driving member rotatable about an axis coincident with the axis of said driven member and comprising two parts connected one to the other, and one of which is mounted for a limited rotatory movement relatively to the other, means to apply power to that part which is capable of said relative movement, an actuating device movably mounted on the other part and connected with the first mentioned part, a connecting device controlled by the movement of said actuating device to connect said driving member with said driven member, and means controlled by the movement of said relatively movable part to lock said device against movement.
28. The combination with a rotatable driven member, of a driving member rotatable about an axis coincident with the axis of said driven member and comprising two parts connected one to the other, and one of which is mounted for a limited rotatory movement relatively to the other, means to apply power to that part which is capable of said relative movement, an actuating device movably mounted on the other part and connected with the first mentioned part, a connecting device controlled by the movement of said actuating device to connect said driving member with said driven member, a locking device held normally in locking engagement with said actuating device, and means actuated by the relative movement of said parts to release said locking device.

ment of said relatively movable part to move said locking device into an inoperative position.

29. The combination with a rotatable driven member, of a driving member comprising a part mounted for rotation about the axis of said driven member, and a second part connected with said first mentioned part and capable of a limited rotatory movement relatively thereto, means to apply power to said second part of said driving member, an actuating device pivotally mounted on the first part of said driving member and connected with the second part thereof, connecting devices carried by said actuating device and adapted to be moved into and out of operative relation with said driven member by the pivotal movement of said actuating device, and means controlled by the relative movement of said second part to lock said actuating device against said pivotal movement.

30. The combination with a rotatable toothed member, of a driving member comprising a part rotatable about the axis of said toothed member, and a second part connected with the first part and capable of a limited rotatory movement relatively thereto, means to apply power to said second part of said driving member, an actuating device pivotally mounted on the first part of said driving member and having an elongated opening therein, a pin carried by the second part of said driving member and extending through said elongated opening, pawls carried by said actuating device and adapted to be moved alternately into and out of operative relation with said toothed member by the pivotal movement of said actuating device, a locking device mounted on said first part and held normally in locking engagement with said actuating device, said locking device having a part arranged adjacent to the elongated opening in said actuating device and adapted to be engaged and actuated by said pin when said second part moves relatively to said first part.

31. The combination with an axle, wheels loosely mounted on the respective ends of said axle, toothed members rigidly secured to said wheels, and means for rotating said axle, of driving mechanism comprising two parts arranged adjacent to each of said toothed members, one of said parts being rigidly secured to said axle and being capable of a limited movement relatively to the other part, pawls carried by said other part and arranged to be moved alternately into engagement with the adjacent toothed member and means controlled by the movement of said relatively movable part to shift said pawls from one position to the other.

32. The combination with an axle, wheels loosely mounted on the respective ends of

said axle and means for rotating said axle, of driving mechanism comprising two parts arranged adjacent to each of said wheels carried by said axle, one of said parts being connected with said axle and being capable of a limited rotatory movement relatively to the other part, and means controlled by the relative movement of said parts to operatively connect the last-mentioned part with the adjacent wheel when the first-mentioned part is rotated in either direction.

33. The combination with an axle, wheels loosely mounted at the respective ends thereof, and means for rotating said axle, of driving mechanism comprising a part arranged adjacent to each of said wheels, connections between said parts and said axle, said connections being such as to permit said axle to have a limited rotatory movement relatively to said parts, and means controlled by the relative movement of said axle and said parts to operatively connect said parts with the respective wheels when said axle moves forward relatively to said parts, and to disconnect the same and maintain the same disconnected when said wheels run ahead of said axle.

34. The combination with an axle, wheels loosely mounted at the respective ends of said axle, toothed members secured to the respective wheels, and means for rotating said axle, of driving mechanism comprising parts arranged adjacent to the respective toothed members, connections between said part and said axle, said connections being such as to permit said axle to have a limited rotatory movement relatively to said parts, a pair of pawls carried by each of said parts, the pawls of each pair being arranged to move alternately into engagement with the adjacent toothed member, and means controlled by the relative movement of said axle and said parts to shift said pawls from one position to another, and to prevent one pawl of each pair from engaging its toothed member when the other pawl of that pair is disengaged from said toothed member.

35. The combination with an axle and a toothed member rotatable about the axis thereof, of a driving member comprising a part mounted about said axle adjacent to said toothed member and a second part mounted about said axle and capable of a limited rotatory movement relatively to the first part, means to apply power to said second part of said driving member, a pawl carried by said driving member and movable into engagement with said toothed member to operatively connect the same with said driving member, and a device connected with the second part of said driving member and arranged to act on said pawl to cause the same to be positively moved into

driving engagement with said toothed member.

36. The combination with an axle and a toothed member rotatable about the axis 5 thereof, of a driving member comprising a part mounted about said axle adjacent to said toothed member, and a second part mounted about said axle and capable of a limited rotatory movement relatively to the 10 first part, means to apply power to said second part of said driving member, a pair of oppositely extending pawls carried by said driving member and movable into and out of driving engagement with said toothed

member to operatively connect the same with 15 said driving member, said pawls being so arranged that when one is moved into operative engagement with said toothed member the other will be moved out of engagement therewith, a device connected with 20 said second part of said driving member and arranged to act on said pawls to cause the same to be positively moved into and out of driving engagement with said toothed member.

25 In testimony whereof, I affix my signature hereto.

ISAAC S. DEMENT.
